[57] CLAIM

The ornamental design for a hand shower and massage brush, as shown and described.

DESCRIPTION

FIG. 1 is a side elevational view of a hand shower and massage brush showing my new design;
FIG. 2 is a rear perspective view thereof;
FIG. 3 is a front perspective view thereof; and
FIG. 4 is a perspective view of a brush attachment of the hand shower and massage brush showing my design.

FIG. 1

FIG. 4
